UNITED STATES PATENT OFFICE.

HOWARD H. WIXON, OF CHICAGO, ILLINOIS, ASSIGNOR TO STROMBERG MOTOR DEVICES COMPANY, OF CHICAGO, ILLINOIS, A CORPORATION OF ILLINOIS.

MAGNETO IGNITION DEVICE.

1,075,531.

Specification of Letters Patent.

Patented Oct. 14, 1913.

Application filed March 4, 1910. Serial No. 547,190.

To all whom it may concern:

Be it known that I, HOWARD H. WIXON, a citizen of the United States, residing at Chicago, in the county of Cook and State 5 of Illinois, have invented a certain new and useful Improvement in Magneto Ignition Devices, of which the following is a full, clear, concise, and exact description, reference being had to the accompanying 10 drawings, forming a part of this specification.

My invention relates to electric generators, commonly known as magnetos, for the ignition of the combustible mixtures in gas 15 engines, and is particularly adaptable for use in connection with gas engines employed for the propulsion of automobiles.

The object of my invention is to provide a magneto-generator in which the various 20 parts are arranged with great compactness, presenting a structure occupying a comparatively small amount of space without sacrificing anything in the line of efficiency, thereby securing many mechanical and electrical advantages.

Among the main features which characterize my invention may be here mentioned: (1) a stationary induction winding having both primary and secondary coils; (2) an 30 interrupter so constructed that the primary circuit is interrupted, first by one pair of contacts and then by another, in order to distribute the injurious effect of the sparking among the several contacts, whereby the 35 life of the interrupter-contacts is greatly prolonged; (3) the provision of a rotatable spark-gap in the secondary circuit in parallel with the spark-plugs of the cylinders, this spark-gap constituting not only a 40 safety-gap but at the same time performing the function of a testing-gap to determine the relation of the moment of sparking with respect to the position of the cylinder-piston. These and other features will be 45 readily understood by a consideration of the several views shown in the accompanying drawings, in which:

Figure 1 is a longitudinal cross-sectional view taken approximately on line 1-1 of 50 Fig. 2, certain of the parts being, for the sake of clearness, shown in full lines; Fig. 2 is a transverse cross-sectional view approximately on the line 2-2 of Fig. 1, certain of the parts being shown in full for the sake 55 of clearness; Fig. 3 is a fragmentary front

view of the upper portion of the machine, showing the distributor in place on the machine, certain of the parts being, for the sake of clearness, shown in cross-section; Fig. 4 is a cross-sectional view, in plan, 60 taken on line 4-4 of Fig. 1, and showing the interrupter casing in position on the magneto; Fig. 5 is an interior view of the interrupter; Fig. 6 is a longitudinal cross-sectional view of a portion of the armature 65 shaft, showing the laminations in the shaft; Fig. 7 is an end view of the main framework of the machine as detached from the associated parts; Fig. 8 is a side view of the main framework, and Fig. 9 is a dia- 70 gram of the circuit connections.

Referring to Figs. 7 and 8, the main framework of the magneto-generator comprises a non-magnetic base-portion 1, which, in practice, would ordinarily be made of 75 brass, a pair of magnetic side-portions 2 and 2' secured to the base-portion, and a non-magnetic top-portion 3 attached to the side-portions. In Fig. 8 is shown fastening means in the form of screws 4 for holding 80 the parts of the framework together. The magnetic side-portions 2 and 2' constitute the pole-pieces, with which the permanent magnets 5 are in good magnetic contact. In the specific embodiment of the machine set 85 forth in the drawings I have shown three pairs of permanent horse-shoe magnets for the field-magnets, but the precise number of such magnets to be employed may, of course, be varied, depending upon the strength of 90 the field which it is desired to secure in any particular machine. The main framework has the central cylindrical bore or space 5', the sides of which form the polar faces 6 and 6'. In this cylindrical space within the 95 framework is arranged a stationary induction-winding 7, comprising the inner or primary coil 8 and the outer or secondary coil 9. Suitable insulation separates the coils from each other and also surrounds the outside of 100 the coils, as indicated cross-sectionally in Fig. 1. This induction-winding is a unitary part which may be readily inserted in place in the magneto and as readily withdrawn therefrom, after the other parts located in 105 the cylindrical spacing have been removed, as will hereinafter appear. The central ridge 8' on the outside of the winding is just sufficiently smaller in diameter than the space in the framework to permit the wind- 110

ing being inserted within the framework and held stationary therein. In order to properly guide the winding in place when it is inserted within the framework of the magneto, suitable guiding means is provided, which, in the specific instance shown, consists of a lug 9' carried by the winding and a coöperating groove 9^a provided at a suitable point on the framework within the cylindrical space, as indicated in Figs. 2 and 7. As a further locking means for the winding when in place, a spring-pressed lug 11 supported in the framework by the screw-threaded tube 12 is adapted to enter a recess 13 in the peripheral ridge of the winding. Upon withdrawal of the winding the yielding-lug 11 will be forced out of the recess. By thus providing guiding and locking means for the winding it will always be possible to place the winding upon the machine in exactly the same position. This is important when it is considered that upon the outside of the winding are located the terminals which are intended to engage certain contact members, as will be described subsequently, mounted at certain points on the machine. In order that the exposed terminals of the coils of the induction winding may register with the contacts carried by the framework, it is, of course, necessary that the position of the winding on the magneto be always the same with respect to the contacts. This sameness of position is insured by some such suitable guiding and locking means as above described.

Passing axially through the winding is the armature shaft 10 rotatably supported in bearings 11' and 12'. The bearing 11' is carried by the rear end-plate 13' secured to the framework of the machine, while the bearing 12' is mounted in the support 14, held in the front end-plate 15. Anti-friction rollers 16 and 17 work in the bearings 11' and 12', respectively. A pair of segmental polar-extensions 18 and 19 are secured to the armature shaft at opposite ends of the winding. In the particular instance illustrated, the armature is screw-threaded at 20 and 21, and the polar-extensions are mounted on these screw-threaded portions, locking screws 22 and 23 being provided on the polar-extensions to prevent accidental disarrangement of the polar-extensions after they have been fastened in position on the armature shaft. Any other approved means of securing these polar-extensions to the armature shaft may be obviously employed, although the screw-threaded engagement between the parts has the advantage of readily permitting axial as well as radial adjustment of the polar-extensions on the armature shaft. The polar-extensions as well as the armature shaft are of magnetic material—at least that portion of the armature shaft which is included between the polar-

extensions. It will therefore be seen that the armature shaft constitutes a rotatable magnetic core for the stationary induction-winding. The angular position of the polar-extensions 18 and 19 on the armature shaft is such that they lie substantially diametrically opposite, as indicated in Fig. 1. In order to provide a large surface on the faces of the polar-extensions I preferably form the latter substantially as shown in Fig. 1, from which it will be seen that the polar-extensions are provided with axial elongations 18' and 19', respectively, these elongations projecting into the space 7' formed between the winding and the surrounding surface of the main framework. By this arrangement the length of the machine is reduced, since, if the elongations of the polar-extensions projected outwardly away from each other, it would be necessary to lengthen the pole-pieces accordingly, or else materially reduce the length of the induction-winding, and thus reduce the efficiency of the machine.

The operation of the machine thus far described will be apparent to those skilled in the art. As the armature is rotated or oscillated the magnetic flux of the field will be periodically short-circuited through the winding, first in one direction and then in the reverse direction. This short-circuiting of the flux takes place when the polar-extensions are moving opposite the pole-pieces, as indicated in Fig. 2, where the polar-extension 18 is shown in a position 90° from the position indicated in Fig. 1. When the armature is in the position shown in Fig. 2 the magnetic flux will pass, (assuming the polarities of the magnets as indicated by N and S), from the pole-piece 2 into the polar-extension 18, through the winding in a direction away from the observer, returning by way of the polar-extension 19 to the opposite pole-piece 2'. When the armature is in a position 180° from that indicated in Fig. 2, the magnetic flux will be reversed through the stationary winding, passing from the pole-piece 2 into the polar-extension 19, through the armature in a direction toward the observer, and returning through the polar-extension 18 into the south pole-piece 2'.

When the inductor is set in rotation an electromotive force is induced in the winding by the action of the field magnet. If now the primary coil is short-circuited, the current flowing therethrough generates lines of magnetic force which largely neutralize the existing magnetic field,—that is, they force back or oppose a change of magnetism through the coil. As soon as the circuit in the primary is broken, the counteraction of the generated opposing flux ceases. Owing to the change which thereby instantaneously arises in the number of the lines

of force passing through the secondary coil from the field magnets, the potential rises so high in the secondary coil that a spark is produced across the spark-plug to ignite the explosive mixture in the engine cylinder.

The wire in the primary coil is comparatively coarse, and comprises comparatively few turns, while the wire constituting the secondary coil is comparatively fine, and comprises a comparatively large number of turns, in order that the electromotive force generated in the secondary coil may be sufficiently high to cause sparking at the spark-plugs of the engine cylinders. This is a matter of mere mathematical calculation to those skilled in the art, and no further explanation is necessary here on this point. The flux-carrying portion of the armature shaft is laminated at 10' in order to obviate or reduce to a minimum the eddy-currents set up by the flux variations. This avoids undue heating of the armature metal and consequent waste of energy. The laminations lie, of course, in the plane of the polar-25 extensions of the armature, as indicated in Figs. 2 and 6. In order to sacrifice nothing of the rigidity of the armature shaft, only the major portion of the latter is laminated, the laminations 10' being secured in the cut-away portion 10². Of course, if desired, the flux-carrying portion of the shaft may consist entirely of laminæ, and suitably secured to the solid end-ports of the shaft.

The armature shaft 10 has an extension 24, to which is rigidly secured the arm 25, having at its opposite ends a pair of rollers 26 and 27 pivoted at 28 and 29, respectively. These rollers are insulated from the arm by insulating bushings 30 and 31, as shown in Fig. 1. This arm, with its oppositely-disposed engaging surfaces, shown as rollers in the specific embodiment illustrated, constitutes the movable contact member of my interrupter. Just how this contact member co-operates with the circuit contacts of my interrupter is best illustrated in Fig. 5, which shows the various parts that go to make up my interrupter mechanism. To the cylindrical support 32 are secured the movable spring contacts 33 and 34, which co-operate with the stationary contacts 35 and 36, respectively. Springs 37 and 38 hold the movable contacts 33 and 34 in firm engagement with their respective stationary contacts, although the resiliency of the movable contacts may be made sufficiently strong to dispense with the auxiliary springs 37 and 38. The cylindrical support 32 is of good conducting metal, such as brass, and the movable contacts 33 and 34 are electrically connected with this support. The stationary contacts 35 and 36 are carried by metallic lugs 39 and 40, respectively, which lugs find bearing in the outer metallic plate 41. This outer plate constitutes a cover for

the cylindrical support 32, and these two parts may be said to constitute a cylindrical casing. The insulating disk 42 wholly insulates the cylindrical support 32 from the cover-plate 41, with the result that the movable contacts 33 and 34 and their respectively fixed contacts 35 and 36 are electrically connected in parallel. It will be apparent from Fig. 5 that the rollers 26 and 27 of the interrupter-arm are of unequal size, so that the oppositely-disposed engaging surfaces of this arm may be said to be at unequal distances from the axis of rotation. The purpose of this arrangement is to cause the interruption of the primary circuit, in which the interrupter is included, first by one pair of contacts and then by the other pair, in order that the burden of sparking may be distributed between the two pairs of contacts. It is clear that in this way the life of the contacts is practically doubled, and the interrupter will endure substantially twice as long as it would if there were but a single pair of contacts for interrupting the primary circuit. If we assume the rotation of the interrupter-arm as indicated by the arrow in Fig. 5, it will be seen that the contacts 33 and 35 will first be separated. However, this will cause no interruption of the primary circuit, for the reason that the circuit is still closed through the parallel path which includes the other pair of contacts, namely, the contacts 34 and 36. As the arm continues its rotation the roller 27 will come into engagement with the movable contact 34 and separate the same from the stationary contact 36, while the other pair of contacts is still held separated by the roller 26. This separation of the contacts 34 and 36 interrupts the primary circuit, thereby causing the induction of a high electromotive force in the secondary circuit to fire the charge in the proper engine cylinder. As the arm 25 continues its rotation, the roller 27 will be the first to release its associated movable contact, and the circuit will be closed, almost instantaneously after its interruption, through the contacts 34 and 36. This will be followed in quick succession by the closure of the parallel path which includes the other pair of contacts 33 and 35. When the interrupter-arm reaches a position 180° from that shown in Fig. 5, it will be clear that the larger roller 26 will first open the parallel path which includes the contacts 34 and 36. However, this will not interrupt the primary circuit, because the circuit is still closed through the parallel path which includes the switch-contacts 33 and 35. As soon as the smaller roller 27 separates the contact 33 from the contact 35 (which will, of course, take place while the contacts 34 and 36 are held separated by the roller 26), the primary circuit will again be inter- 130

rupted, and whatever sparking will take place at this moment of interruption will be across the contacts 33 and 35. By thus causing interruption of the primary circuit, 5 first through one pair of contacts and then through the other pair, the life of the interrupter is practically double that of those interrupters in which but a single pair of contacts is employed. And this advantage is 10 secured by so arranging the two pairs of contacts and the interrupter-arm that the cyclical actuation of the contacts takes place in succession, the circuit being interrupted alternately by one pair and then the other 15 pair of contacts.

In order that the interrupter-casing may be readily attached to the magneto and as readily removed therefrom, a bearing-plate 43 is rotatably mounted in the front end-plate 15, as shown in Figs. 1 and 4. Through the opening 44 in this bearing-plate passes the extension 24 of the armature shaft 10. This rotatable bearing-plate carries two oppositely-disposed lugs 45 and 46 screwed into the plate. These lugs are provided with head-portions 47 and 48 and with insulating portions 49 and 50. The cylindrical support 32 is provided with two oppositely-arranged enlargements or bosses 51 provided with openings 52. The cover-piece 41 carries a cross-bar 53. A pair of openings 54 extends through the cover-piece and the bar 53 in alinement with the openings 52, as best seen in Fig. 4. Into the 30 openings 54 extend the projections or buttons 55, which are pressed outwardly by suitable springs 56. When it is desired to insert the interrupter-casing in place on the magneto, it is only necessary to bring the 35 openings of the casing into alinement with the lugs 45 and 46 and press the casing inwardly until the parts are in the position shown in Fig. 4, when the buttons 55 will rest in the grooves of the head-portions 47 and 48 of the lugs 45 and 46. This produces 40 a separable locking engagement between the rotatable base-plate 43 and the interrupter-casing. As shown in Figs. 1 and 4, the front end-plate 15 is provided with a circular 45 shoulder 15', which forms a housing for the interrupter-casing. An insulating disk 57, preferably secured to the base-plate 43, insulates the latter from the cylindrical support 32 of the interrupter-casing. From this 50 it will be seen that the stationary contacts 35 and 36 are grounded to the magneto, while the movable contacts 33 and 34 are insulated therefrom. The binding-post 58 is carried by the end-plate 15 and insulated 55 therefrom by an insulating-bushing 59, as shown in Fig. 4. This binding-post makes electrical contact with the cylindrical support 32, and therefore with the movable contacts 33 and 34 carried by said support. 60 This is diagrammatically indicated in Fig. 65

9, which also shows the stationary contacts 35 and 36 grounded to the machine at G. The detailed description of this figure will be taken up later on in due course. The object of having the interrupter radially adjustable is to vary the moment of sparking with respect to the position of the engine cylinder. Since the armature shaft is driven by the engine, and since the interrupter-arm 25 is driven by the armature, it will be apparent that by rotating the interrupter-casing the moment at which the circuit will be interrupted by one of the pairs of contacts may be varied with respect to the position of the engine cylinder, or (which amounts to the same thing) with respect to the position of the armature. In order to get the best sparking it is customary to so time the moment of circuit-interruption that it will occur substantially at the moment of 70 generation of maximum electromotive force, which (as is well known) takes place when the armature is about to interrupt the magnetic short-circuit through the induction-winding, or at least reduce it to a minimum. 75 In my magneto this will take place when the armature is substantially in the position in which it is shown in Fig. 1, or in a position 80 180° therefrom. In order to facilitate the adjustment of the interrupter-casing I have 85 provided an arm 60, arranged at right-angles to the bar 53 and removably attached to the interrupter-casing in any suitable manner. In the present instance the cover-plate 41 of the interrupter-casing carries a 90 pair of lugs 61, which enter openings 62 in the arm 60, the spring-pressed buttons 63 providing a separable locking engagement 95 between the two parts. The arm 60 has an extension 64 provided with an opening 65 to afford connection with the timing lever of the automobile equipment, or with some other suitable part which the driver of the machine may conveniently operate to adjust 100 the time of ignition. 105

I come now to the distributor which forms part of the magneto outfit. For the sake of illustration, it has been assumed that the precise embodiment of my magneto-generator illustrated in the drawings is for a 110 four-cylinder engine, and, therefore, the distributor is shown as provided with four contacts 66, 67, 68 and 69 mounted in the insulating ring 70. Each contact is electrically connected with a contact-terminal 115 71 by conductor 72. From the terminals 71 connections lead to the spark-plugs of the engine cylinders. Insulating thimbles 73 protect the upper portions of the contact-terminals 71. The supporting-ring 70 and 120 the contact-terminals 71 are carried by a base-plate 74 of insulating material. A correspondingly-shaped cover-plate 75, also of insulating material, is arranged to fit over 125 the base-plate 74, as indicated in Fig. 1, to 130

inclose the parts and thereby protect them from liability to injury. Screws 76, passing through openings 77 in the base- and cover-plates, secure what may be termed the stationary part of the distributor to the end-plate 15. Within the cylindrical space 78, formed by the ring 70, moves the annular member 79 of insulating material. A glass or mica-plate 80 carried by the cover 75 is provided in front of the cylindrical space 78. The member 79 has fixedly mounted thereon the metallic arm 81, which terminates at its outer end in an arc-shaped engaging surface 82, forming part of the periphery 83 of the annular member 79, as best shown in Fig. 3. At its inner end the metallic arm 81 is in electrical contact with extension 84 of the shaft 85. It is on this extension 84 that the annular member 79 is suitably secured, as by screw-threaded engagement. An insulating-bushing 86 is fixed upon the member 79 by having its shank portion 87 inserted in an opening in the annular member, as cross-sectionally shown in Fig. 1. The front portion of the bushing 86 serves to cover up the arm 81. This bushing carries spark-electrode 88, whose shank portion 89 has electric connection with the metal disk 90, which is preferably fixed to the insulating member 79. The projection 91 on the extension 84 cooperates with the electrode 88 to form a spark-gap. I will subsequently explain how this spark-gap forms a combined safety and testing spark-gap. For the present let us proceed with a description of the remaining structural features of my magneto-generator. The shaft 85 is housed within the insulating tube 92, which may, in actual practice, be perhaps preferably constructed of two parts, fitted into each other as indicated in Fig. 1. The screw-threaded end 93 of the shaft 85 is inserted in a thimble 94, which is fixed within the tube 92. A metallic contact-ring 95 is mounted upon the tube 92, and electrically connected with the shaft 85 by a conducting-pin 96. A metal tube 97 is fitted over one end of the insulating tube 92 to provide support for the race-way 98, in which are located the rollers 99 which work in the bearing-ring 100. This ring is supported in the recess portion 101 of the end-plate 15. From this it will be seen that the electrode 88 is electrically grounded to the framework of the machine through the disk 90, the metallic tube 97, against which the disk 90 abuts, and through the roller-bearing just described. The other electrode 91, on the other hand, has electrical engagement with the metallic ring 95, which is insulated from the framework of the machine. The other end portion of the insulating tube 92 is connected with the metallic shaft 102, having a recess 103, into which extends the reduced portion 104 of the tube 92. A pin 105 is inserted through the parts to prevent relative rotation thereof. At an intermediate point the shaft 102 has mounted thereon the race-way 106 for the anti-friction rollers 107, which work in the bearing-ring 108. This ring is mounted in the recessed portion 109 of the bearing-plate 110. The end-plate 13' and the bearing-plate 110 are recessed to form a housing 111, in which is located the large gear 112 fixed upon the end of the shaft 102. The metal shaft 102, the insulating tube 94, and the metallic tube 97 may be said to constitute as a whole the distributor-shaft which operates the annular member 79. A gear 113 fixed upon the armature shaft is in mesh with the gear 112, thus communicating the rotation of the armature shaft to the distributor-arm 81 and to the movable spark-gap formed by the electrodes 88 and 91 which move in synchronism with the distributor-arm. The gear-ratio between the gears 113 and 112 is such that the gear 113 makes two revolutions to every revolution of the gear 112. As the distributor-arm 81 is rotated its engaging surface 82 makes electrical contact with the projecting points 114 of the contacts 66, 67, 68 and 69. Preferably, these projecting points, or buttons, as they might be termed, are mounted resiliently, so that good contact may be insured between them and the distributor-arm 81.

Referring to Fig. 8, the cut-away portions 115 and 116 at opposite ends of the top member 3 are for the purpose of accommodating the recessed portion 109 on the bearing member 110 and the recessed portion 101 on the front end-plate 15. Besides being provided with the longitudinal opening 117 to accommodate the distributor shaft, the top member 3 is also provided with the vertical openings 118 and 119 for the purpose of accommodating the insulating terminal block 120. The axial opening 121 through said block is to accommodate the distributor-shaft. The lower portion of the insulating-block has mounted therein the contact-button 122, which is pressed against the contact-ring 95 by the spring 123. Through this spring the contact-button has connection with an outer contact-button 124, which is adapted to make electrical engagement with the terminal 125 of the secondary winding 9, as diagrammatically indicated in Fig. 2. It will therefore be seen that the distributor-arm 81, as well as the electrode 91, are electrically connected with the terminal 125 of the secondary winding 9. This connection, which has already been described structurally in connection with Fig. 1, is diagrammatically indicated by the conductor 126 in Fig. 9. The insulating-block also carries the contact 127, which is normally pressed outwardly by the spring 128 located in a recess in the insulating-block. 130

The contact 127 is located within the hollow extension 129, which is suitably secured to the insulating-block as by screw-threading. The binding-post 130 makes metallic connection with the contact 127 through the spring 128. The contact 127 makes electrical engagement with the terminal 131 of the primary winding 8, as indicated diagrammatically in Fig. 2. The binding-post 130 is for connection with one terminal of the condenser 132 conveniently supported within the magneto on the top member 3. In the diagram of Fig. 9, the conductor 133 represents the connection between the binding-post 130 and one terminal of the condenser, while the conductor 134 represents the connection between the binding-post 130 and the terminal 131 of the primary winding. In the bottom of the base-portion 1 is secured the contact-terminal 135 insulated from the machine by the insulating-bushing 136. The object of this contact-terminal 135 is to make connection with the terminal 131 of the primary winding through the conductor 137, as diagrammatically indicated in Figs. 2 and 9. The terminals 135 and 58 are adapted to be electrically connected, and this connection is diagrammatically indicated in Fig. 9 by the conductor 138. Inasmuch as the contact-terminal 58 is electrically connected with the movable contacts 33 and 34 of the interrupter, it is apparent that the condenser 132 is connected in parallel with the interrupter. Referring again to Fig. 2, the other terminals of the primary and secondary windings are grounded to the machine, as diagrammatically indicated at 139. In the actual construction of the induction-winding, the terminal-conductors 125, 131, 137 and 139 are preferably made of flat ribbon, and terminate in fixed positions on the periphery of the insulation which covers the winding. It will now be appreciated why it is necessary that the armature be always inserted on the magneto in a predetermined position. So far as the grounding-terminal 139 is concerned, this would make contact with the metal of the machine in various positions of the armature, but the terminal-conductors 125, 131 and 137 must fall in place opposite the contacts 124, 127 and 135, respectively. This registering of the terminal-conductors and the contacts is insured by the guiding means for the armature, as previously explained.

There remain to be described the circuit connections shown in the diagrammatic view of Fig. 9, together with the operation of the system. Most of the parts shown in Fig. 9 have already been referred to in connection with the description of certain structural features of my magneto. In order, however, to complete the description of what is shown in Fig. 9, I will add that to the common

ground G, which may be said to represent the metal of the machine, are connected the other terminal of the condenser by the conductor 140, the other terminals of the primary and secondary windings by the conductors 141 and 142, respectively, and the stationary contacts 35 and 36 by the conductor 143. The ground for the electrode 88 carried by the movable member of the distributor is indicated at 144. The distributor contacts 66, 67, 68 and 69 are connected by conductors 145, 146, 147 and 148, respectively, to the electrodes 149 of the spark-plugs. The other set of electrodes 150 is connected to ground, as indicated at 151. The parallel connection of the movable contacts 33 and 34 of the interrupter is indicated by the ring-conductor 32', which is supposed to represent diagrammatically the cylindrical support 32 on which the movable contacts are mounted. The conductor 152 represents the electrical connection between the binding-post 58 and the cylindrical support indicated diagrammatically by 32'. The parallel connection of the fixed contacts 35 and 36 is indicated by the conductors 153 and 154, which are connected to the common conductor 143. It will be apparent, from a consideration of the circuit arrangement shown in Fig. 9, that the condenser is connected in parallel with the interrupter, that the pairs of interrupter-contacts are connected in parallel with each other, and that the electrodes 88 and 91 are arranged in parallel with the electrodes of the cylinder spark-plugs. The object of having the condenser in parallel with the interrupter is, as is well known by those skilled in the art, to prevent as much as possible the sparking at the electrodes which interrupt the primary circuit, and also to increase the voltage in the secondary circuit by accelerating the flux variations through the induction-winding. I have previously stated that the electrodes 88 and 91 constitute a combined safety and testing-gap. How they constitute a safety-gap is apparent from the fact that these electrodes are in parallel with the electrodes of the spark-plugs, so that if for any reason the current should fail to leap across the electrodes of the spark-plug which the distributor has connected in the circuit of the secondary winding, the secondary current surging through the secondary circuit under high pressure would leap across the spark-gap formed by the terminals 88 and 91, thus discharging the secondary circuit with safety. Otherwise, there would be danger of the secondary voltage driving the current through the insulation of the induction-winding. The testing feature of the spark-gap formed by the electrodes 88 and 91 is brought about by the fact that the spark-gap rotates in unison with the distributor-arm and in alinement 130

therewith, so that by disconnecting a cylinder spark-plug from the distributor and operating the magneto the position of the spark that will pass across the electrodes 88 and 91 will indicate at what position of the engine piston the moment of sparking is occurring. If the sparking is too early or too late the interrupter may be readily adjusted in the manner previously described.

10 Of course it is obvious that this rotatable testing-gap does not depend for its advantage and utility upon the other features of my invention, and I therefore claim the same broadly. Similarly does my novel form of interrupter not depend for its utility upon the presence of the other features of my invention herein described, as will be apparent from certain of the appended claims.

20 Having thus described my invention, what I claim as new and desire to secure by Letters Patent of the United States is:

25 1. In a magneto-generator, a non-magnetic base-portion, a pair of magnetic side-
portions secured to said base-portion and forming pole-pieces, a non-magnetic top-
portion secured to said pole-pieces and pro-
vided with a longitudinal opening, said four
30 portions constituting a hollow frame-work,
magnets in contact with said pole-pieces, a
stationary generator winding arranged
within said framework, an unwound armature
35 rotatable within said framework and having
extensions passing over the periphery of the
winding for reversing the magnetic
flux through said winding, an inter-
rupter carried on the framework at one end
40 and operated by the armature shaft, a dis-
tributer also carried on the framework at
the same end, an operating shaft for said
distributer passing through the opening in
the top-portion of said framework, and a
45 gear connection between said two shafts at
the other end of such framework.

50 2. In a magneto-generator for ignition
purposes, the combination of a framework,
magnets supported thereby, a pair of end-
plates secured to said framework, a distrib-
uter and an interrupter mounted one above
55 the other upon one of said end-plates, a
generator winding between said magnet
ends, a rotatable armature having exten-
sions passing over the periphery of the
winding for reversing the magnetic flux
60 through said winding, a shaft on which said
armature is mounted, said shaft operating
the interrupter, a second shaft for oper-
ating the distributer, and gearing at the other
end-plate for connecting said shafts to-
65 gether.

3. In a magneto-generator, the combina-
tion of a magnetic field-frame, a generator
winding disposed therein, a rotatable arma-
ture for reversing the magnetic flux through
65 said winding, a shaft for said armature

70 journaled in the ends of said field-frame, a
radial arm secured to one end of said shaft,
a plurality of contacts disposed in proxim-
ity to said arm, a casing in which said con-
tacts are mounted to be actuated by said
75 arm, a rotatable base-plate carried by the
field-frame concentrically with the arma-
ture axis, and means for securing locking
engagement between said casing and said
base-plate when the casing is placed in posi-
75 tion on the magneto, said means permitting
ready removal from the casing.

4. In a magneto-generator having a field-
frame, a generator-winding and an arma-
ture, the combination of a rotatable base-
plate mounted in one end of the field-frame
concentrically with the armature axis, a
80 pair of lugs extending axially from said
base-plate, a cylindrical casing provided
with openings for receiving said lugs when
the casing is inserted in place on the mag-
neto, whereby engagement is secured be-
tween the casing and the base-plate to per-
mit radial adjustment of the casing and
ready removal thereof from the magneto, a
90 plurality of circuit-contacts carried by said
casing, and an interrupter-arm operated by
the armature shaft for actuating said con-
tacts.

5. In a magneto-generator, a non-mag-
netic base-portion, a pair of magnetic side-
portions secured to said base-portion and forming
pole-pieces, a non-magnetic top-
portion secured to said pole-pieces and pro-
vided with a longitudinal opening, said four
100 portions constituting a hollow framework,
magnets in contact with said pole-pieces, a
stationary generator winding arranged
within said framework, an unwound armature
105 rotatable within said framework for
reversing the magnetic flux through said
winding, an interrupter carried on the
framework at one end and operated by the
armature shaft, a distributer also carried
110 on the framework, an operating shaft for
said distributer passing through the open-
ing in said top-portion, said shaft having
an insulated portion, a hollow block of in-
sulating material secured in said top-portion,
115 the distributer-shaft passing through said
block, contact members carried by said
block and having connection with said wind-
ing, a contact-ring mounted on the insulated
portion of the distributer-shaft and con-
nected with a metallic portion thereof, said
120 contact-ring engaging one of said contact
members, and a gear connection between
said shafts.

6. In a magneto generator, a field frame,
a stationary generator winding arranged
within said frame, an unwound armature
rotatable within said frame and having ex-
tensions passing over the periphery of the
winding for receiving the magnetic flux
through said winding, an interrupter car-
130

ried on the frame at one end and operated by the armature shaft, and a distributor also carried on the frame at the same end.

7. In a magneto generator, a field frame, 5 a stationary generator winding arranged within said frame, an unwound armature rotatable within said frame and having extensions passing over the periphery of the winding for receiving the magnetic flux 10 through said winding, an interrupter carried on the frame at one end and operated by the armature shaft, a distributor also car-

ried on the frame at the same end, an operating shaft for said distributor passing through an opening in said frame, and a 15 gear connection between said two shafts at the other end of said frame.

In witness whereof, I hereunto subscribe my name this 1st day of March, A. D. 1910.

HOWARD H. WIXON.

Witnesses:

CHARLES A. BROWN,
A. A. THOMAS.
